UNITED STATES PATENT OFFICE.

GEORGE H. CARDELL, OF RENO, NEVADA.

PATTERN-DRAFTING DEVICE.

984,347.

Specification of Letters Patent. Patented Feb. 14, 1911.

Application filed November 30, 1909. Serial No. 530,598.

To all whom it may concern:

Be it known that I, GEORGE H. CARDELL, a citizen of the United States, residing at Reno, in the county of Washoe and State of Nevada, have invented certain new and useful Improvements in Pattern-Drafting Devices, of which the following is a specification, reference being had therein to the accompanying drawing.

This invention relates to drafting instruments, and the principal object of the same is to provide an instrument for drawing patterns for cylindrical sheet metal articles, such as cones, ellipses, frustums, pipe elbows, and the like.

In carrying out the objects of the invention generally stated above, it is contemplated providing a frame composed of a body member and end members, the end members being of different sizes and adjustably connected to said body member to permit various relative adjustments, said end members being provided with adjustable making means for imparting the end lines of a pattern to the usual drawing paper so that said ends may be readily connected by the usual ruling instruments.

It will be understood, of course, that in the practical application of the invention, the essential features thereof are necessarily susceptible of changes in details and structural arrangements, certain preferred and simple embodiments of which are shown in the accompanying drawings, wherein—

Figure 1 is a bottom plan view of the improved instrument. Fig. 2 is a view in elevation of one end thereof. Fig. 3 is a similar view of the opposite end. Fig. 4 is a detail plan view of one end of the body member, showing an attachment therefor. Fig. 5 is a view in side elevation of the structure shown in Fig. 4. Fig. 6 is a view similar to Fig. 3, but showing the instrument reversed and equipped with needle points. Fig. 7 is a detail view of an ellipse attachment for the instrument. Fig. 8 is a fragmentary view, partly in section, showing the construction of the marking wires of the instrument. Fig. 9 is a perspective view of the instrument showing the same in use for laying out a pattern.

Referring to said drawings by numerals, 1 designates the flat elongated body member of the instrument that is provided with a central longitudinal slot 2. Said body member, as well as the other parts of the

instrument to be described, are preferably of sheet metal, and one end of said body may be reduced and extended to form a resilient socket 3 into which one end of an upturned arm 4 is snugly but removably fitted. The other end of said arm is provided with a sleeve 5 for the reception of a needle point 6 that may be used as a pivot upon which the body 1 may be swung. Said body has its longitudinal edges provided with graduations to designate inches and fractions thereof.

An end member 7 having graduations on its longitudinal edges and a central longitudinal slot 8 is adjustably held in engagement with one end portion of the body member 1 by the bolt 9 and thumb screw 10, said bolt also passing through a protractor plate 11, the ends of which are clamped to member 7 by the bolts 12 and thumb nuts 13. One end of said member is provided with an outstanding sleeve 14 which is preferably formed of two sections of resilient material, the sections thereof being held in adjustable clamping relation by the adjusting screw 15. A sleeve 16 is adjustably clamped to the member 7 adjacent its other end by means of the plates 17—18 and bolt 19 and thumb screw 20. Said sleeves 14 and 16 project at right angles to the member 7, the sleeve 14 being stationary, and the sleeve 16 being adjustable and provided with a clamping screw 21. A marking wire 22, formed of spring metal having an inclosing jacket 22^a of rubber or the like has one end clamped within sectional sleeve 14, its other end being bowed over member 7 and passed through the slot 8 thereof and adjustably clamped within sleeve 16 by the screw 21. Said marking wire is equipped with graduations representing inches and fractions thereof. Another end member 7^a, that is a duplicate of end member 7 excepting that it is larger, has a bolt and thumb-nut engagement 24—25 with member 1, and has a protractor 26 held thereto by means of bolt and thumb nut 24—25, and by the similar end bolts and thumb nuts 27—27^a. Said member 7^a is also equipped with a stationary sectional sleeve 28 at one end, and an adjustable sleeve 29 adjacent its other end, both sleeves being identical with the sleeves 14—16 of end member 7, and adjustably supporting a bowed wire 30 that is also similar to the wire 22 of said end member 7. In Fig. 9 the instrument has been shown

in use for laying off patterns for cylindrical articles that taper longitudinally. The length and diameter of the article being known, end members 7 and 7^a are adjusted 5 on body member 1 to the desired length, and the wires 22-30 are adjusted in their sleeves to the diameter of the article. Said wires are then inked and the end members 7-7^a are held against one edge of the board 10 31 with the wires resting on the drawing paper 32. The instrument is then rocked on the paper 32, causing the wires to mark the ends of the pattern as indicated on the paper, after which the ends of the lines 15 marked on the paper are connected as indicated by broken lines.

If a cone is to be drawn, one of the end members is removed and the other adjusted to the length of the cone. In this use of 20 the instrument the needle point 6 of the member 1 is used to indicate the apex of the cone on the drawing paper, and the marking wire indicates the base.

To lay off a square, or straight edge, the 25 sleeves of members 7 and 7^a may be equipped with needle points 33 instead of the marking wires, as is suggested in Fig. 6. As will be obvious, the use of needle points in laying off squares and cones, causes said 30 needle points to perforate the paper.

As is indicated by dotted lines in Fig. 2, and shown in detail in Fig. 7, the means for drawing ellipses comprises a rod 34 for each marking wire, said rod having a sleeve 35 at one end for engaging the marking wire and its other end threaded as indicated at 36 for adjustable engagement with the thumb nut that holds the end members in engagement with the body member 1. In 40 drawing ellipses, the long and short diameter being known and the end members set therefor, by adjusting rods 34 the marking wires will be flexed to the desired shape of the ellipse.

45 It will be understood, from the foregoing that the improved instrument by means of the described manner of adjustably connecting the parts thereof may be used for laying off various patterns, of which those 50 noted in the foregoing are examples.

What I claim as my invention is:-

1. An instrument of the character described, comprising a body member, end members therefor, means for pivotally and 55 adjustably connecting said members to said body, and adjustable marking means carried by each member and connecting opposite portions thereof.

2. An instrument of the character described, comprising a body member, end members therefor, means for pivotally and 60 adjustably connecting said members to said body, protractors carried by the end members for indicating the angular positions of 65 said members relative to said body, and

marking means adjustably connecting opposite portions of said end members.

3. An instrument of the character described, comprising a body, end members therefor, means for adjustably and pivotally 70 connecting said members to said body, marking wires for said members, means for rigidly connecting one portion of said wires to one portion of said members, and means for adjustably connecting an opposite portion of said wires to an opposite portion of 75 said members.

4. An instrument of the character described comprising a body member, end members adjustably and pivotally connected 80 therewith, a stationary clamping sleeve for one end of each end member, an adjustable clamping sleeve carried by the other end portion of each end member, and marking means adjustably supported by said sleeves. 85

5. An instrument of the character described comprising a body member, end members having an adjustable pivotal connection therewith, a stationary clamping sleeve at one end of each end member, an 90 adjustable sleeve carried by the other end portion of each of said end members, and a bowed marking wire for each end member having its ends adjustably supported by the said sleeves. 95

6. An instrument of the character described comprising a body member having a central longitudinal slot, end members similarly slotted, means for holding said end members in adjustable pivotal engagement with said body member, a protractor for each end member, for indicating its angular position relative to the body member, and marking means carried by each end member. 100

7. A pattern drafting instrument, comprising a body, end members therefor, means for pivotally and adjustably connecting said members to said body, and adjustable marking means carried by and connecting opposite portions of said members, and adapted to be rocked across a drawing surface to lay out the ends of a pattern. 110

8. An instrument of the character described comprising a body, end members adjustably connected thereto, and an ink-receiving marking-wire adjustably connecting opposite ends of each end member. 115

9. An instrument of the character described, comprising a body, bowed ink-receiving marking wires for the ends thereof, and means for adjustably and pivotally connecting the said wires to said body. 120

In testimony whereof I hereunto affix my signature in presence of two witnesses.

GEORGE H. CARDELL.
